UNITED STATES PATENT OFFICE.

EDGAR L. DRINKWATER AND GEORGE C. DAVISON, OF CHICAGO, ILLINOIS; SAID
DAVISON ASSIGNOR TO SAID DRINKWATER.

DRAWING BOARD.

Application filed June 26, 1924. Serial No. 722,573.

To all whom it may concern:

Be it known that we, EDGAR L. DRINKWATER and GEORGE C. DAVISON, residing at Chicago, in the county of Cook and State 5 of Illinois, respectively, have invented certain Improvements in Drawing Boards, of which the following is a specification.

Our invention relates to tackless drawing boards and is particularly adapted to the 10 smaller boards of sizes up to approximately 19" x 27".

One of the objects of our invention is to provide a drawing board of the type having a frame with paper retaining means extending 15 over the interior edges of the frame and overlying a movable panel normally engaging the retaining means, the retaining means being so arranged that two interior edges of the frame are unrestricted so 20 as to enable the drawing sheet to be inserted from above the frame, one end at a time, between the edges of the panel and the retaining means.

Another object of the invention is to provide 25 a drawing board of the type above referred to in which the end portions of the panel may be flexibly depressed from engagement with the retaining means to permit the insertion of the sheet, the center portion 30 of the panel, however, being fixed with respect to the working face of the frame so as to present a substantially rigid drawing surface.

Other and further objects of the invention 35 will more fully hereinafter appear. For drawing boards holding standard size sheets say 10" x 15", such as are used in preparing a Patent Office drawing, we have found the construction shown very desirable.

Our invention will be more fully understood 40 by reference to the accompanying drawing which shows a preferred form of the device and in which

Figure 1 is a plan view of a panel drawing-board showing our improved construction.

Fig. 2 is a longitudinal section taken on line 2-2 of Fig. 1.

Fig. 3 is a view similar to Fig. 2, but 50 showing a modified construction, in which only a single panel is used.

Fig. 4 is an enlarged fragmentary view of the construction shown in Fig. 2.

Fig. 5 is an enlarged fragmentary view 55 of the construction shown in Fig. 3.

Referring to the drawings, it will be seen that the board comprises a frame 1 and a panel or panels 2. The frame 1 has the sides 3-3 and ends 4-4 suitably mitred and mortised to form rigid corner joints. 60 Flush metal retaining plates 5 are provided at each corner of the frame, these retaining plates, in the form of the invention shown in Fig. 2, being arranged on both the upper and lower surfaces of the frame so as to 65 overlie and underlie the panel opening for the purpose of supporting and limiting the panel movement. If desired, additional retaining plates, such as 5^a, may be similarly arranged at the ends of the frame as shown 70 in Fig. 1. The retaining plates 5-5^a serve as clips to hold the drawing paper in place upon the panel 2.

As shown in Fig. 2, and also as indicated in dotted lines in Fig. 1, each of the panels 2 is recessed or countersunk at suitable points so that springs 7 may be inserted in the countersunk portions to supply pressure for holding the panels 2 apart and in contact with the plates 5-5^a. Preferably, the 75 springs 7 will be located at the corners of the panels and, in case additional retaining plates, such as 5^a, are provided, springs may also be positioned near the edges of the panels underlying such retaining plates. With 80 the springs 7 thus arranged, the panels 2-2 are supported from each other, and spring pressure is maintained between the working surfaces of both panels and the retaining plates 5-5^a. Both panels may be used for 85 drawing.

The ends of the spring 7 may, if desired, be set in depressions or flanged metal cup receptacles 7^a in the panels 2-2 as indicated 90 in detail in Fig. 4. These flanged receptacles 7^a hold the spring 7 in position and also prevent the springs from pushing off the outer layer of veneer when a veneered panel is used. The receptacles 7^a further provide a recess in which the coil spring 7 compresses without crushing, and thereby allows 95 the panels 2-2 to be depressed closely back to back, thus gaining the space otherwise occupied by the compressed spring for additional capacity when it is desired to carry 100 reserve sheets of paper.

As shown in Fig. 4, the plates 5-5^a on either surface of the frame are suitably apertured and countersunk to receive male and female screws 8 and 9 which pass there- 110

through and firmly reinforce the joint when used as corner plates. Regular wood screws may also serve for securing the retaining plates on the frame when desired.

5 While in our drawings we have shown retaining plates 5—5 at the four corners of the board and between the corners, as shown at 5^a—5^a, it is wholly within the scope of the invention to use any combination of 10 plates that may be found advantageous. For example, it is not required that the retaining plates 5—5 be positioned at the corners of the panel opening, although this is a desirable construction. The retaining 15 plates may be placed with equal advantage intermediate the corners, overlying and underlying opposite sides of the panel opening. Neither is it necessary for successful operation that the plates of the two surfaces 20 of the frame be placed opposite each other, although a desirable construction consists in securing them, through the frame, to each other in pairs, as shown.

The portion of the panel retaining plates 25 5—5^a and 6—6^a recessed into the frame 1 is preferably of circular shape and greater than 180°, as shown. This makes it possible to recess the frame in one operation with a bit, to receive the flush plates, and, with a 30 circumference of greater than 180° recessed into the frame, the plate is retained against any lateral motion, even though the screw holes through the frame be somewhat larger than the body of the screw.

35 It is desirable in drafting to keep the surface of the paper flush or slightly lower than the T-square, and to provide this advantage we have secured the strips 10—10 supporting the panel at a proper fixed height by recessing the strips into saw cuts 11—11 in the sides 3—3 of the frame, as shown in Figs. 1 and 2. These strips 10—10 may be 40 of equal service by attaching them by means of screws 11'—11' to the sides 3—3 of the frame, as indicated in dotted lines in the 45 lower part of Fig. 1. These supporting strips 10—10 not only provide a stationary rest for the panel and oppose warping of the panel, but they also serve as a fulcrum upon 50 which the panel may be sprung to insert the paper beneath the retaining plates 5—5^a. The omission of these supporting strips for one panel of the double panel board allows the surface of such panel to depress equally 55 at all points, so that reserve sheets of drawing paper may be carried on such panel for field use.

The paper, being cut approximately the 60 size but not larger than the opening in the frame, is secured on the board in the following manner: The paper whose edges are indicated by the dotted lines *a*, *a*¹, *a*², and *a*³ is placed in proper position on the board ready 65 to insert one edge of the sheet, as indicated by the dotted line "*a*" in Fig. 1, beneath the

retaining plates 5—5 at the corresponding corner or side of the frame 1. One edge of the panel 2 is then slightly depressed at *b*—*b*', and at the same time the paper is slipped under the retaining plates 5—5^a, 70 bringing the edge of the sheet "*a*" against the inside edge of the frame while keeping the adjacent edge of the sheet *a*¹ snugly against the corresponding adjacent inside edge of the frame. The opposite edge or 75 corners of the sheet are then inserted beneath the respective retaining plates in a similar manner. It will be observed that by arranging the retaining plates opposite 80 interior edges only of the frame the two interior side edges of the frame are free and unrestricted, so that the ends of the paper may be separately inserted under the retaining plates from above the frame without bending or flexing the paper in more than 85 one direction.

It is evident that the two edges of the paper *a*² and *a*³ need not fit as accurately as the edges *a*—*a*¹, and preferably the panel is $\frac{1}{16}$ " to $\frac{1}{8}$ " larger than the standard size 90 sheets to allow for variations either in the cutting of paper or due to atmospheric conditions. Sheets somewhat smaller either way than the panel size will also be securely held in place without additional retaining 95 plates.

In this way the sheet is held flat, rigidly gripped between the four or more upper retaining plates, and the panel is easily removed and may be readily and accurately 100 replaced. At no point does the surface of the paper lie above the surface of the frame, preventing rubbing and thus keeping the paper clean. Scale and gauge marks may be made on the frame for marginal, center 105 guide lines, etc. The frame is preferably properly squared from all four sides, thereby making four outer working edges. No end grain is presented to the T-square, and a frame so constructed will remain true, for 110 any shrinkage is necessarily uniform throughout.

A modified arrangement is shown in Figs. 3 and 5 in which but a single panel 2 is provided. In this case the retaining plates 115 5 and 5^a (where the latter are provided) will only be arranged upon the upper working face of the frame 1, the side members 3—3 and end members 4—4 being rabbeted as shown at 13 to form a support for the 120 springs 7. Preferably, the rabbets 13 will be recessed or countersunk so that when the panel 2 is depressed the spring may be compressed into the recess. The retaining plates 5, as shown in Figs. 3 and 5 are secured by 125 ordinary wood screws 9'. If desired, the underside of the frame may be covered with felt or other suitable material as indicated at 12 in Figs. 3 and 5.

The modification just described possesses 130

the advantages previously recited in connection with the arrangements shown in Figs. 2 and 4 and, in addition, is a somewhat simpler and less expensive construction. It requires a smaller number of retaining plates, and the provision of the rabbeted portion of the members of the frame involves no mechanical difficulty whatever.

10 While we have shown herein our preferred construction, we do not wish to be understood as limiting ourselves thereto as we realize that many modifications might be made without departing from the spirit 15 of this invention as defined in the following claims.

What is claimed is:

1. In a drawing board, a frame having interior dimensions substantially corresponding to a drawing sheet, retaining means projecting from the face of the frame and over the interior opening thereof near two edges only so that the other two interior edges are separated through substantially 25 their entire length by a distance at least equal to the width of the sheet, a panel mounted in said frame, the edges of said panel engaging said retaining means and being flexibly held thereagainst, and a portion of said panel intermediate said edges being fixed with respect to the working face of said frame, said panel being adapted to have said edges pressed away from the retaining means whereby the sheet 30 may have one edge inserted from above the frame between the panel and retaining means at one edge of the frame and the opposite edge of the sheet then inserted from above between the panel and retaining 35 means at the opposite edge of the frame.

2. In a drawing board, a frame having interior dimensions substantially corresponding to a drawing sheet, retaining means projecting from the face of the frame and over the interior opening thereof near two edges only so that the other two interior edges are separated through substantially 45 their entire length by a distance at least equal to the width of the sheet, a panel mounted within said frame, spring members to flexibly hold two edges of said panel in engagement with said retaining means, and means for fixedly positioning a portion of said panel intermediate of said edges with respect to the working face of the frame, the edges of said panel being adapted to be pressed away from the retaining means whereby the sheet may have one edge inserted from above the frame between the panel and retaining means at one edge of the frame and the opposite edge of the sheet then inserted from above between the panel and retaining means at the opposite edge of the frame.

3. In a drawing board, a frame having in-

terior dimensions substantially corresponding to a drawing sheet, a retaining plate recessed in the face of the frame at each corner thereof and having a portion projecting from the interior opening of the frame, the portion of said plates recessed in said frame being an arc greater than 180° for the purpose of preventing lateral motion of the plates, a panel mounted in said frame and flexibly held against the projecting portions of said retaining plates, means to fix a portion of said panel intermediate its ends with respect to the working face of said frame, the ends of said panel being adapted to be pressed away from the retaining plates whereby the drawing sheet may have one edge inserted from above the frame between the panel and retaining plates at two corners of the frame and the opposite edge of the sheet then inserted from above between the panel and retaining plates at the opposite corners of the frame.

4. In a drawing board, a frame having interior dimensions substantially corresponding to a drawing sheet, retaining means projecting from each face of the frame and over the interior opening thereof near two edges only so that the other two interior edges are separated through substantially 50 their entire length by a distance at least equal to the width of the sheet, a pair of panels mounted within said frame, said panels being maintained in spaced relationship and having their ends flexibly held against said retaining means so that they may be pressed away from the retaining means, means to fix a portion of said panels intermediate its ends with respect to the working face of said frame, whereby the sheet may have one edge inserted from above the frame between the panel and retaining means at one edge of the frame and the opposite edge of the sheet then inserted from above between the panel and retaining 55 means at the opposite edge of the frame.

5. In a drawing board, a frame having interior dimensions substantially corresponding to a drawing sheet, retaining means projecting from the face of the frame and over the interior opening thereof near two edges only so that the other two interior edges are separated through substantially 60 their entire length by a distance at least equal to the width of the sheet, a pair of panels mounted within said frame, springs arranged between the panels to maintain them in spaced relationship and flexibly hold them against said retaining means, means to fix a portion of said panels intermediate its ends with respect to the working face of said frame, said panels being adapted to be pressed away from the retaining means whereby the sheet may have one edge inserted from above the frame between the panel and retaining means at one edge of the frame and the opposite edge of the sheet then inserted from above between the panel and retaining means at the opposite edge of the frame.

- the frame and the opposite edge of the sheet then inserted from above between the panel and retaining means at the opposite edge of the frame.
6. In a drawing board, a frame having interior dimensions substantially corresponding to a drawing sheet, retaining means projecting from each face of the frame and over the interior opening there-
10 of near two edges only so that the other two interior edges are separated through substantially their entire length by a distance at least equal to the width of the sheet, a pair of panels mounted within said frame,
15 two edges of each of said panels being flexibly held in spaced relationship and against the corresponding retaining means, and a

portion of one of said panels between said edges being fixed with respect to the working face of the frame, said panels being 20 adapted to be pressed away from the retaining plates whereby the drawing sheet may have one edge inserted from above the frame between the panel and retaining plates at two corners of the frame and the opposite 25 edge of the sheet then inserted from above between the panel and retaining plates at the opposite corners of the frame.

In testimony whereof, we have signed our names to this specification this 24th day of 30 June, 1924.

EDGAR L. DRINKWATER.
GEORGE C. DAVISON.
